UNITED STATES PATENT OFFICE.

CHESTER E. WALKER, OF PEORIA, ILLINOIS.

DESIGN FOR A PRIE DIEU.

Application filed June 9, 1922. Serial No. 2,599. Term of patent 3½ years.

To all whom it may concern:

Be it known that I, CHESTER E. WALKER, a citizen of the United States, residing at Peoria, in the county of Peoria and State of Illinois, have invented a new, original, and ornamental Design for a Prie Dieu, of which the following is a specification, reference being had to the accompanying drawing, forming part thereof.

The figure is a perspective view of a prie dieu, showing my new design.

I claim:

The ornamental design for a prie dieu, as shown.

CHESTER E. WALKER.
